UNITED STATES PATENT OFFICE.

EDWARD E. NICODEMUS, OF SILVIS, ILLINOIS.

HAT-FASTENER.

1,188,304.

Specification of Letters Patent. Patented June 20, 1916.

Application filed August 31, 1915. Serial No. 48,324.

To all whom it may concern:

Be it known that I, EDWARD E. NICODEMUS, a citizen of the United States, residing at Silvis, in the county of Rock Island and State of Illinois, have invented certain new and useful Improvements in Hat-Fasteners; and I do hereby declare the following to be a full, clear, and exact description of the invention, such as will enable others skilled in the art to which it appertains to make and use the same.

This invention relates to the toilet, and more especially to hat fasteners; and the object of the same is to produce a pin structure permanently carried within the crown of the hat and operated by a handle projecting through the side of the crown and having a knob so that it simulates the head of the ordinary hat pin. This object is carried out in the manner hereinafter more fully described and claimed, and as shown in the accompanying drawings wherein:

Figure 1 is a sectional view through an ordinary sailor hat showing this fastener stitched therein with its pins in the position they assume when they engage in the wearer's hair. Fig. 2 is a perspective view showing the fastener on an enlarged scale removed from the hat, the pins in this view being shown in the position they occupy when they are withdrawn from the hair as in the act of putting on or taking off the hat. Fig. 3 is plan view of the fastener with the pins in the same position as shown in Fig. 1, the handle in this instance being shown as projecting in the opposite direction.

I have illustrated the invention as applied to an ordinary sailor hat having a brim B and a crown C and when these hats are worn by ladies they usually have a lining indicated at L. The prevailing means for attaching such a hat to the head is to run the point of a hat pin transversely through the crown and lining, and engage it with the hair, the result being that the head at one end and the point at the other end of the pin are exposed on opposite sides of the crown. This custom has its objections in the puncturing of the crown, the fact that the pin point is sometimes pushed into the scalp, and the danger that the projecting and unprotected point affords.

In the present invention I make use of a framework member, preferably of wire, stitched inside the crown above the lining

if there be one, and entirely out of sight; and on this framework is rotatably mounted a second member, also preferably of wire, which includes two arcuate pins capable of being moved in their own arcs and projected through the lining and engaged with the hair; while a third member serves as a handle and is connected at one end with the second member and has its other end projecting slidably through the side of the crown and carrying a knob or ornament on its extremity to simulate the head of an ordinary hat pin.

My preferred manner of carrying out this idea is as follows: The skeleton framework may well be made of a single piece of wire whose center is left straight to constitute an axle 1, and at each end of the axle the wire is bent at point 2 into a horizontal stretch 3, then bent downward as at 4 into a foot 5, then carried inward in a horizontal stretch 6 and finally engaged with the axle 1 at the point 7; and the two points 7 at the ends of the wire from which this framework is made are preferably separated slightly so that the handle (described below) may play freely between them. The other member of this hat fastener rocks on the skeleton framework just described, and by preference it also is made of a single piece of wire. The latter is bent at each end into an arcuate pin 10, one end of which is pointed as at 11 and the other end of which is formed into a spoke 12 extending thence inward to the center of the arc, looped loosely as at 13 into eyes embracing the axle near its bend 2, and then carried over the axle on a line oblique thereto in a bail 14 which has a loop 15 midway between the two pins and at the center of the stretch of wire from which this member is made. When the parts stand as seen in Fig. 3, the bail 14 is on the opposite side of the axle from the two stretches 6 of the framework and the pins underlie said framework as seen in Fig. 1.

Coiled on each half of the axle between the points 2 and 7 is a spring 20, one end of which is engaged at 21 with the stretch 6 of the framework while the other end is engaged at 22 with the bail 14; and the tension of these springs is such as to normally raise the points of the pins above the positions they occupy in Figs. 1 and 3.

A handle 24 completes the structure, and is by preference made of a single stretch of stiff wire having a loop 25 at its inner

end which is loosely engaged with the loop 15 of the bail, and a bend 26 near the loop 25 so that the latter will not become cramped in the loop 15 in action. Beyond the bend 5 26 the handle 24 is led over the axle 1, then through the crown C at the point 26, and its outer extremity by preference carries an ornamental button or knob 27 which simulates the head of the ordinary hat pin. This 10 knob may be made removable, and applied to the outer end of the handle after the device has been put in place.

In operation the framework is stitched into the crown or otherwise fastened there- 15 to in about the position shown, and the parts stand normally as seen in Fig. 1. When now the hat is put onto the head, the operator draws on the knob 27 with the result that the rocking member swings around the 20 axle of the framework where it is hinged thereon by the two eyes 13, and the arcuate pins are retracted so that their points 11 are drawn backward and upward through the lining L (if there be a lining) to the 25 position shown in Fig. 2. The hat is then put on, and by releasing the knob or by bearing the same inward, the pins are ad- 30 vanced through part of the circle in which they stand and through the hair and re- 35 stored to the position shown in Fig. 1 where they are held under the tension of the springs 20. The hat is now firmly fastened in place, and the fastener cannot become ac- 40 cidentally detached because the springs are yet under some tension which is resisted 45 where the handle 24 crosses the axle 1. However, it is possible, as shown in Fig. 3, to have the handle 24 lead in the opposite direction and out through the other side of 50 the crown, but in that case the knob would have to be pushed instead of pulled in the application of the device as just described. I have also made use of this view to show 55 how the feet 5, which in Figs. 1 and 2 are simple angles, might be amplified or given various shapes so as to adapt them to other hats than sailors or, in fact, so that they could be bent by the purchaser to adapt them to almost any hat. Attention is di- 60 rected to the fact that the points 11 of the pins are formed by beveling off the wire on the outer side of the arc-shaped pin- bodies. This is purposely done so that when the pins are projected through the hair 65 the bevels will strike the scalp and the ex- treme points will not enter it.

What I claim is:

1. In a hat fastener, the combination with a framework adapted to be fastened within 60 the hat crown and including in its structure a horizontal axle; of a rocking mem-

ber having eyes rotatably mounted on said axle, spokes radiating from the eyes, and pins projecting from the outer ends of said spokes and struck on arcs around said axle, 65 a bail connecting said eyes, and a handle leading from the bail through the crown to the exterior thereof.

2. In a hat fastener, the combination with a framework adapted to be fastened within 70 the hat crown and including in its structure a horizontal axle; of a rocking member having eyes rotatably mounted on said axle, radial spokes, arcuate pins projecting from said eyes around said axle, a bail 75 whose ends extend from said eyes inward obliquely to the axle and whose center has a loop, and a handle slidably mounted through the side of the hat crown and having a loop at its inner end engaging that on 80 the bail and a bend adjacent its loop to prevent the loops from cramping, and a knob at its outer end.

3. In a hat fastener, the combination with a framework comprising a horizontal axle 85 bent at its ends into stretches, thence formed into feet adapted for attachment to the inside of the hat crown, and finally formed into horizontal stretches connected at their extremities with said axle; of a rocking 90 member comprising arcuate pins, a spoke leading inward from one end of each pin and looped into an eye loosely embracing said axle near its end, a bail connecting said eyes, a handle leading from the center of 95 the bail whereby this member may be rocked on the axle, and a spring coiled on the latter with one extremity engaging one of said stretches and the other engaging the bail.

4. In a hat fastener, the combination with 100 a skeleton framework including a horizontal axle, two stretches projecting horizontally therefrom at spaced points near the center of the axle, and depending feet on 105 these stretches adapted to be stitched to the interior of a hat crown; of a rocking member comprising a bail, eyes at its ends rotatably mounted on said axle, arcuate pins carried by said eyes, springs coiled on the 110 axle and each having one extremity connected with one of said stretches and the other with said bail, and a handle connected with the center of the bail and extending thence over the axle between said points and through one side of the hat crown. 115

In testimony whereof I affix my signature in presence of two witnesses.

EDWARD E. NICODEMUS.
